WATCHCASE

Ellison S. Irelan, Elgin, Ill., assignor to Illinois
Watch Case Company, Elgin, Ill., a corporation
of Illinois

Application May 25, 1934, Serial No. 727,481

3 Claims. (Cl. 58—88)

This invention relates to a two-piece watch case having therein a removable seat for the support of a movement. The advantages inherent in such a watch case are its simplicity of construction, the fewness of its parts, the facility with which it may be opened up for removal or replacement of the movement, and the accommodation therein of various movements as desired.

10 An exemplification of my invention is set forth in the accompanying drawing wherein—

Figure 1 is a view in plan of my present watch case accommodating therein a movement whose dial is exposed to view;

15 Fig. 2 is a transverse section on line 2—2 of Fig. 1;

Fig. 3 is a transverse section through the angled plane indicated by line 3—3 of Fig. 1; and

20 Fig. 4 is a sectional perspective view showing the movement ring, back, and seat ring in assembled relation.

The case herein illustrated comprises a back A which, if desired, may be of irregular contour. As shown, the back is formed with an outwardly 25 extended well 5 of circular form. Extending in a direction opposite from the well is a marginal flange 6.

Fitted within the back flange 6 is a movement ring B having a contour the same as that of the 30 back. This movement ring is extended past the marginal back flange 6 so as to be exposed in part. By any well known means, the movement ring is preferably secured fixedly to the back so as to constitute therewith a two-piece case. An 35 inwardly turned flange 7 defining a circular opening 8 is provided at the exposed end of the movement ring.

Associated with the case just described is a bezel C which carries a crystal 9. The bezel is 40 formed with a marginal flange 10 which fits down over the movement ring to meet the marginal flange 6 of the back. As by means of a groove 11 in each end of the bezel flange and a co-acting rib 12 on the movement ring, the bezel may be 45 snaplocked in position on the case.

Certain of the usual fittings which have no bearing on this invention may also be added, such as lugs 14 at opposite ends of the bezel for connection with a bracelet, and a sleeve 15 50 through one side of the case for the accommodation of a winding stem.

Fitted within the circular well of the back A is a seat ring 16. This ring may be removably accommodated in place. It protrudes beyond the 55 well a sufficient distance to afford a desired support against which may be rested the shoulder 17 of a movement M. The circular seat ring is concentric with the circular opening 8 in the movement ring flange which is adapted, if need be, to 60 afford lateral support to the circular wall of the

movement whereon may be carried a dial plate 18 which is adapted to extend over the movement ring flange, as required, to conform to the irregular contour of the case.

From the preceding description it will be observed that the present case makes use of but two parts, viz, a back and a movement ring which together with a seat ring fitted within the back furnishes a support for a circular movement. A wide latitude is accordingly afforded in the contours available for the case. Removal of the bezel is all that is required for removal or replacement of the movement. When completely assembled, the case has but one joint, viz, the connection between the bezel and the movement ring, but this is so lapped as to protect the case interior against the entrance of moisture, dust, etc.

I claim:

1. A watch case in which is comprised a back having a marginal flange, a movement ring fitted within and extending beyond the back flange, a bezel having a flange extended over the movement ring to meet the back flange, a snap-lock connection between the bezel flange and the movement ring, and a seat ring fitted within the back to the inside of the movement ring furnishing a support for the shoulder of a movement which is accommodated within the case.

2. A watch case in which is comprised a back having an outwardly extended well and a marginal flange extended oppositely thereto, a movement ring fitted within and extending beyond the back flange, a bezel having a flange extended over the movement ring to meet the back flange, and a seat ring fitted within the back well to the inside of the movement ring affording a support for the shoulder of a movement which is accommodated within the case.

3. A watch case in which is comprised a back of irregular contour having a marginal flange, a movement ring of like contour fitted within and extending beyond the flange at which point it is formed with an inwardly turned flange defining a circular opening, a bezel having a flange extended over the movement ring to meet the back flange, and a seat ring defining a circular opening concentric with that of the movement ring fitted within the back to the inside of the movement ring affording a seat for the shoulder of a movement which is accommodated within the case.

ELLISON S. IRELAN.
